DESIGN FOR A DOLL

Oscar Ball, New York, N. Y.

Application April 17, 1945, Serial No. 119,048

Term of patent 3½ years

(Cl. D34—4)

To all whom it may concern:

Be it known that I, Oscar Ball, a citizen of the United States, residing in New York city, in the county of New York and State of New York, have invented a new, original, and ornamental Design for a Doll, of which the following is a specification, reference being had to the accompanying drawing, forming part thereof.

Fig. 1 is a front view of a doll showing my new design,

Fig. 2 is the rear view thereof, and

Fig. 3 is a side view thereof, on a reduced scale.

I claim:

The ornamental design for a doll, substantially as shown.

OSCAR BALL.
